UNITED STATES PATENT OFFICE

2,043,658

FOOT CONSTRUCTION FOR DOLLS OR
THE LIKE

Tana Graicer, Philadelphia, Pa.

Application October 4, 1934, Serial No. 746,766

7 Claims. (Cl. 46—151)

My invention relates to the construction of feet for dolls, manikins and similar articles.

A purpose of my invention is to facilitate the construction of weighted doll's feet by enclosing the weight within a covering of pliable material, such as paper, securing said weight at the legs by means of the pliable material.

A further purpose is to manufacture at low cost doll's feet which will have a more life-like and attractive appearance than those heretofore made.

A further purpose is to wrap a weight for weighting doll's feet in paper or similar material, to inscribe or impress upon the paper printing or artistic work simulating the appearance of human feet or shoes, and to secure the weight thus covered by tabs glued to the legs.

A further purpose is to cause the feet of a doll to "toe-in" by inserting a tab between the leg and a weight within the foot, on the side opposite to the side toward which the foot is to "toe".

A further purpose is to fold opposite counterpart blanks about weights to form the respective feet of a doll, manikin or the like, and to secure the weights to the legs by tabs from the blanks.

A further purpose is to produce diverging ends on the legs of dolls, manikins or the like for making a securing attachment to a foot covering.

My invention relates both to the methods involved and to the article produced.

In the drawing I have illustrated one only of the many possible variations of my invention, choosing the form shown from the standpoint of satisfactory operation and convenient illustration of the principles involved.

Figure 1 is a front elevation of the feet of a doll, manikin or the like, with a portion of the legs.

Figure 2 is a section of Figure 1 upon the line 2—2 thereof.

Figures 3 and 4 are plan views of the blanks used in making the casings for the right and left feet respectively of the doll.

Figure 5 is a central vertical section of a partially completed right foot construction.

Figure 6 is a central vertical section of the fully completed right foot construction.

Figure 7 is a section of Figure 6 along the line 7—7.

Figure 8 is a perspective view of the weight or dipsie employed in my invention.

55 In the drawing like numerals refer to like parts.

One of the extremely vulnerable portions of most doll constructions is the feet. If the feet are molded of wax, or similar plastic material, they may be given a very life-like appearance, but are generally unlikely to contribute material-

ly to lowering the center of gravity of the doll and thus rendering the doll stable when supported on its own feet. Particularly in the manufacture of dolls from cardboard, pulp board, strawboard, wall board, illustration board, fiber board and other similar products, by whatever name they may be known, resort has been had to various constructions of the feet to render the doll more stable. One of these devices has been to mount the legs on a large base which bears no resemblance to the human foot and is unsatisfactory for that reason. Another plan is to support the legs from skis or long wooden feet which extend both to the front and to the rear of the legs and are relatively stable but 15 awkward and inhuman in appearance.

By my improved foot construction, the feet are weighted by a lead weight known as a weight, and nevertheless the feet present a life-like and rather attractive appearance.

In Figure 1 I show the right leg 20 and the left leg 21 of a doll or manikin. The doll shown is of the type stamped from cardboard or some other type of board, such as one of those mentioned. It is, of course, suitably decorated to 25 present a life-like appearance, and to permit dressing by various paper dresses cut out by the child.

The right foot 22 and the left foot 23 are opposite counterparts, each consisting of a foot 30 casing 24 and a weight 25. The weight has a flat sole 26, a curved toe portion 27, an arched instep portion 28 and a flat heel portion 29. According to my preferred construction, the same weight may be used for both the right and the 35 left foot, though the weights for the two feet may be different if desired.

The blanks for the casings of the right and left feet are opposite counterparts as shown at 30 and 31 in Figures 3 and 4. I will describe 40 the formation of the tabs on the right foot casing 30, applying primes to the similar tabs on the left foot casing 31.

The instep portion 32 of the casing is curved over the instep 28 of the weight, and the inner 45 sole tab 33 is folded down (with respect to the position of blank of Figure 3) about the score line 34 across the sole 26 of the weight as shown in Figures 5 and 6. This leaves the "toeing-in" tab 35 extending toward the rear, as it has not 50 yet been folded down (with respect to the position of Figure 3) about the fold line 36. The outer sole tab 37 is next folded down (with respect to the position of Figure 3) about the score line 38 and over the inner sole tab 33, to which 55 adhesive has been applied. The inner sole tab 33 and the outer sole tab 37 are thus united together by adhesive.

The "Achilles'-tendon" tab 39 is now extended toward the rear as shown in Figure 5, as it has 60

not yet been folded down (with respect to the position of Figure 3) about the score line 40. I next fold the "toeing-in" tab 35 about its score line 36 and up against the flat heel portion 29 5 of the weight, to which it is desirably united by adhesive. The front ankle tab 41 is at the same time folded up (with respect to the position of Figure 3) about its score line 42. The position of the tabs is now as shown in Figure 5.

- 10 The sides of the lower end 43 of the leg 20 (or 21) are outwardly tapered at 44 (Figure 7) so that the extreme lower ends of the legs are wider than the intermediate ankle portions, for the purpose of preventing the foot casing from slipping off. The sides of the foot casings slope at 45 and 46 to fit the taper 44 of the lower ends 43 of the legs.

The foot is now placed against the leg in the position of Figure 5, by movement of the foot 20 toward the right or the leg toward the left in this view until the taper 44 of the leg is engaged by the inner heel tab 47 and the outer heel tab 48 and the "toeing-in" tab 35 rests against the leg at one side. The leg should desirably be secured to all adjoining tabs by adhesive, and this is particularly important in the case of the front ankle tab 41, whose upper curved end 49 desirably indicates the top of a sock or stocking.

25 The inner heel tab 47 and the outer heel tab 48 are next successively folded in (down in the position of Figure 3) close about the lower end 43 of the leg along their fold lines 50 and 51 and glued in place. The tendency is to cause the foot to "toe-in" because the "toeing-in" tab 35 is on one side only, so that the space 52 (Figure 7) is somewhat wedge shaped, and the foot "toes-in". The next operation is to bend up (down in Figure 3) the "Achilles'-tendon" tab 39 about its fold line 40, and secure the tab 39 against the tab 48 and against the rear of the leg by adhesive.

30 The adhesive may be replaced or assisted by metallic fastenings, of which one is shown at 53 passing through the "Achilles'-tendon" tab 39, the outer heel tab 48, the inner heel tab 47 and the lower end 43 of the leg into the soft metal (desirably lead) of the weight.

35 It will be evident that the whole of the casing is united firmly to the leg, holding the weight in a fixed position. The casing has a sabot-like appearance due partly to the angular positioning of the fold line 42 of the front ankle tab. The decoration of the casings may, for example, include shoe lacings 54 as shown in Figure 2, or 40 other suitable printing or art work.

45 It will be evident that the casing and weight are very firmly held to the leg not only by reason of the folds in the casing and the adhesive and/or fastening means, but also because of the 40 tapering of the ends of the leg.

50 While I have described in some detail a specific form of blank and preferred order of folding, it will be evident that other blanks and other 45 orders of folding may be used.

55 Somewhat less desirably, the blank for the foot casing may be part of the blank for the body of the doll. The casing may preferably be heavy paper, although cloth, leather, etc. may be used.

60 It will be evident that the weight, besides performing a weighting function, assists in maintaining the contour of the relatively pliable casing material, and thus produces a very solid foot

construction without the necessity of employing any plastic ingredient to fill out the foot.

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:—

1. The method of forming the foot of a doll, manikin or the like, using a weight of foot-like shape and a casing, which consists in forming on the casing tabs which permit the casing to engage with itself and form a closed body about the weight, in forming on the casing other tabs which permit the casing to engage the leg of the doll, in folding the casing around the weight, in securing together the tabs which permit the casing to engage with itself and in securing to the leg the tabs which permit the casing to engage the leg.

2. The method of forming the foot of a doll, manikin or the like, using a weight of foot-like shape and a casing, which consists in locating the weight in front of the leg, in folding the casing around the weight, in extending between the weight and the leg a tab on the opposite side from that toward which the foot is to "toe" and in securing the casing and weight in the "toed" position to the leg by tabs from the casing.

3. The method of forming the foot of a doll, manikin or the like, using a weight and a casing, which consists in forming a diverging tapered end on the leg of the doll, in placing the weight in front of the leg, in folding the casing around the weight and the tapered portion of the leg to engage the taper and prevent slipping off of the casing from the leg and in securing the casing to the leg.

4. In a construction for the foot of a doll, manikin or the like, a weight of foot-like shape and a casing folded around the weight and around the leg, having tabs which unite it with itself and tabs which unite it with the leg of the doll or the like.

5. A pair of doll's feet formed of weights and opposite counterpart paper blanks folded around the weights and having tabs securing the weights to the legs of the doll.

6. A construction for a doll's foot comprising a weight of foot-like contour and a separate casing folded about the weight, having tabs uniting the casing with itself, having a tab extending between the weight and the doll's leg on one side to cause the weight to "toe" in the opposite direction and having tabs uniting the casing to the 60 doll's leg.

7. In a construction for the foot of a doll, manikin or the like, a doll's leg having an extremity whose sides are tapered and larger at the lowermost end, a weight positioned in front 65 of the extremity of the leg and a casing folded about the weight and about the extremity of the leg, secured to the leg, engaging the tapered portion of the leg and holding the weight in foot-like relation to the leg, whereby the casing is in 70 part prevented from slipping from the leg by its engagement with the tapered portion of the leg.

TANA GRAITCER.
